UNITED STATES PATENT OFFICE.

FRIEDRICH HINDERER, OF NEW ORLEANS, LOUISIANA.

DESIGN FOR A HANGING FLOWER-POT.

SPECIFICATION forming part of Design No. 36,800, dated February 16, 1904.

Application filed January 13, 1904. Serial No. 188,932. Term of patent 7 years.

To all whom it may concern:

Be it known that I, FRIEDRICH HINDERER, a citizen of the United States, residing at 1114 Camp street, New Orleans, in the parish of Orleans, State of Louisiana, have invented a new, original, and ornamental Design for a Hanging Flower-Pot, of which the following is a specification, reference being had to the accompanying drawing, forming part thereof.

10 The figure is a perspective view showing the hanging flower-pot.

What I claim as new and original, and desire to secure by Letters Patent, is—

The ornamental design for a hanging flower-pot, as shown.

FRIEDRICH HINDERER.
